UNITED STATES PATENT OFFICE

96,430

DESIGN FOR A COOKING RANGE

John Allen Underwood, Evanston, Ill., assignor to Montgomery Ward & Co., Incorporated, Chicago, Ill., a corporation of Illinois

Application May 27, 1935, Serial No. 57,041

Term of patent 14 years

To all whom it may concern:

Be it known that I, John Allen Underwood, a citizen of the United States, residing at Evanston, in the county of Cook and State of Illinois, have invented a new, original, and ornamental Design for a Cooking Range, of which the following is a specification, reference being had to the accompanying drawing, forming a part hereof.

In the drawing, the figure is a perspective view of a cooking range showing my new design.

I claim:

The ornamental design for a cooking range, as shown.

JOHN ALLEN UNDERWOOD.
